[57] CLAIM

The ornamental design for a modular holder for display of a compact disc storage case, as shown and described.

DESCRIPTION

FIG. 1 is a front plan view of a modular holder for display of a compact disc storage case according to my invention;

FIG. 2 is a front plan view thereof having a clip attached for attachment of another modular holder thereto;

FIG. 3 is a rear plan view thereof;

FIG. 4 is a rear plan view thereof having a clip attached for attachment of another modular holder thereto;

FIG. 5 is a left side elevational view thereof;

FIG. 6 is a left side elevational view thereof with attached clip;

FIG. 7 is a right side elevational view thereof;

FIG. 8 is a right side elevational view thereof with attached clip;

FIG. 9 is a bottom plan view thereof, the top plan view being a mirror image of FIG. 9;

FIG. 10 is a bottom plan view thereof with attached clip, the top plan view being a mirror image of FIG. 10;

FIG. 11 is a front perspective view thereof; and,

FIG. 12 is a front plan view showing a modular holder of the invention joined with a clip to other said modular holders, shown in broken lines to illustrate the environment of use.

Together with clips bent in the form of a right angle the modular holder allows to build cube like combinations.
